sive, the tab member 23 is placed in the package 16' over the tops of the cigarettes, so that its end 24 projects through a slot 25 formed in the wrapper at the base of the end flap 26, and then the closing of the end flaps 26 and 27 is accomplished in the usual manner. Thereafter, the outer protective covering 28 of Cellophane or other suitable material may be applied to the package as indicated in Fig. 14 and may completely enclose the package including the projection 20 or may in some instances as indicated in dotted lines in Fig. 14 project through a slot in the wrapper similar to the slot 25. With either of the above constructions when the projection 24 is exposed and the user pulls outwardly on it, he will tear out the end flap 26 of the package, and then the other end flaps 27 may be torn out to open up the end of the package as shown in Fig. 15.

With the form shown in Figs. 16 to 26 the tab member 29 has a part 30 placed in the package 31 over the tops of the cigarettes, a part 32 extending down the side of the package and tapering inwardly to the tab 33 which projects out through a slot 34 in the side of the package. The end flaps 35 and 36 are closed over in the usual manner. The outer covering 37, usually a moisture proof Cellophane, is then placed over the package, so that its single thickness end 38 fits over the end having the tab member, and where the tab projects through the package, the outer wrapper or covering 37 is preferably cut out as indicated at 39, and this opening 39 and the tab 33 are preferably covered over by a cover flap 40 of Cellophane cemented to the outer covering and having a free end 41 which may be grasped by the operator to remove said flap 40, so as to expose the tab 33. Grasping the exposed tab 33 of this construction and pulling upwardly on it with the thumb and forefinger of one hand while grasping the package with the other hand with the thumb resting on the end adjacent the tab will cause said tab member to tear out a hole such as 42 in Fig. 26 and to tear out a flap 43 from the package which may be pulled back over the end of the package so as to tear off a part of the end closure. Where as noted above the outer

covering 37 only has a single thickness over the top, the same will be readily torn during the removal of the tab member 29.

The outer coverings 22 and 28 of the previously described forms may have the single thickness end disposed adjacent the tab members 19 and 23, so that the tab may be more easily inserted through a slot in the covering and so that the covering will be easier to tear.

10 I desire it to be understood that this invention is not to be limited to any particular form or arrangement of parts except in so far as such limitations are included in the appended claims.

What I claim as my invention is:

- 15 1. The combination with a package having portions forming an end closure, a removable member loosely mounted in the package having a portion beneath said closure of a width substantially equal to the width of the package and a part disposed inside said package adjacent the side of the package and a tab at its lower end of less width projecting through the side of the package, said part at the side of said package tapering from the end of said package to said tab, the pulling of said tab from the package acting to tear an opening in the end of the package, a covering member for said package having an opening through which said tab projects, and a removable cover flap for covering said tab and said opening.
- 20 2. The combination with a package having portions forming an end closure, a removable member loosely mounted at one end of said package beneath said closure and extending down a distance on one side of said package and disposed inside said package with its lower end formed as a tab projecting through the side of the package and bent against the outside of the package and adapted to be pulled to tear out a part of the side and top at one corner of the package, a covering member for said package having an opening through which said tab projects, and a removable cover flap for covering said tab and said opening and having a tab portion for grasping said flap for its removal.
